UNITED STATES PATENT OFFICE.

ELMER S. OLMSTED, OF BEECHMONT, KENTUCKY, ASSIGNOR TO CHEATHAM ELECTRIC SWITCHING DEVICE COMPANY, OF LOUISVILLE, KENTUCKY.

ELECTRICALLY-CONTROLLED RAILWAY-SWITCH.

1,079,991.

Specification of Letters Patent.

Application filed March 22, 1913. Serial No. 756,142.

Patented Dec. 2, 1913.

To all whom it may concern:

Be it known that I, ELMER S. OLMSTED, a citizen of the United States, and a resident of Beechmont, in the county of Jefferson, State of Kentucky, have invented a new and useful Improvement in Electrically-Controlled Railway-Switches, of which the following is a specification.

This invention relates to electrically controlled railway switches, the same being designed as an improvement upon the devices described and claimed in United States Patents Nos. 612,702, 696,313, 787,827, all granted to Robert V. Cheatham and also upon my Patent No. 978,053. In my said patent is shown and described and claimed a mechanism for locking the switch so that where several cars are operated together by one motorman, or where one car follows another too closely, there will be no danger of having some of the cars of the train switched in one direction and some in another; or of having the track switch moved between trucks of a preceding car. In my said patent is shown and described a mechanism which operates both electrically and mechanically so as to fix a portion of the controller or relay from the time that the first trolley wheel leaves the first trolley pan (or line contractor) until it strikes a second trolley pan (or line contractor) which is farther along the track.

The object of my present invention is to provide a locking device of the same character as set forth in my said patent in a simplified and improved form.

For a more particular description of my invention, reference is to be had to the accompanying drawings, forming a part hereof, in which is shown a diagrammatic view of one embodiment of my invention.

To simplify the drawing, only two trolley pans (or line contractors) are indicated. They may be of any suitable form, either with two fixed and parallel bars or one movable bar, both types being old and well known. When my invention is in use there will be either one or two second trolley pans, as may be required. Where two are used, there will be one for each track, that is, one which will be engaged when the trolley car takes the curve and another which will be engaged when the trolley car goes straight ahead. When only one is used, it is placed just back of the trolley switch. As both

these secondary trolley pans are identical, a description of one will answer for both.

In the Cheatham system referred to in the patents above mentioned, and particularly in Patent No. 787,827, there is employed a trolley pan, or line contractor, 1, a relay or circuit-controller 2 and a double solenoid 3 which is connected to the switch-point rail 4 in any suitable manner, so that when the device is in use when power is applied to the motors of the car, the car will be switched in one direction, and if power be turned off from the motors of the car, the car will be switched in another direction. In the particular embodiment of the present invention as here shown there is a time fuse 6 and a circuit breaker 7, all of which may be as described in said last mentioned patent, or otherwise, as desired.

The trolley pan 1 has a rail 8 connected to the trolley wire through the magnet of the relay 2 by suitable wires 9 and 10. Another rail which is parallel to the rail 8 and designated 11 is connected to the time fuse 6 by means of a suitable wire 12, and this time fuse has a second wire 13 which runs to an electric switch 14, and from this switch 14 another wire 15 runs to the pivot 16 on which a bell crank lever 17 is fulcrumed. This bell crank lever 17 carries a suitable balancing weight 18 and on the same arm is pivotally connected to a core 19 which moves vertically in the magnet of the relay 2 in such a manner that when the magnet of this relay is energized the core 19 is raised. The weight 18 is sufficient to keep any raising from taking place unless a motor current is passing through the magnet of the relay 2. Under normal conditions when no motor current is passing through the relay 2 the bell crank lever 17 has its upper or free end resting against a pivoted contact 20 which is rigidly connected to a suitable arm 21 and pivotally mounted at 22. The arm 21 is slotted or perforated so as to permit a vertical rod 23 to slide vertically therethrough, this rod being guided at its lower end in the magnet of the circuit breaker 7 and at its upper end by means of a suitable guide 24. This rod 23 carries a bracket 25 which is adjustably and fixedly mounted thereon, and also, if desired, a suitable weight 26. The lower end of this rod 23 passes into a mercury cup, as set forth in said Patent No. 787,827. A wire 27 connects the magnet of

the circuit breaker 7 with the pivot 22 and a second wire 28 connects this magnet with the double solenoid 3 so that one coil of said solenoid may be energized by current passing through the wire 28. A fixed stop 29 limits the movement of the bell crank lever 17 when the core 19 is raised, and this stop 29 has a wire 30 which runs direct to a second coil of the double solenoid 3 so that this 10 second coil may be energized through said wire.

The switch 14 has two contacts 31 and 32 united by a suitable jaw 33 when the mechanism is in the position shown. This jaw 33 is rigidly connected to the core 34, which is non-magnetic, except for the part 35 which is made of iron or other suitable magnetic material. This core 34 passes into a double solenoid with two coils 36 and 37, both of which are on a common axis. The coil 36 has one terminal connected to both of the secondary trolley pans 38, only one of which is shown. The trolley pan 38 has two bars which are parallel, one 39 being connected by a wire 40 to the coil 36 and the other, a bar 41, being connected by a suitable wire to the trolley wire 42. The coils 36 and 37 are connected to the ground by a suitable wire 43. The coil 37 is connected by a wire 44 to a small stud bar 45 of the trolley pan 1. This bar 45 is parallel with the bar 8 and near one end of the bar 11. A trolley wheel 46 is shown connecting the bars 8 and 11. It runs, when the apparatus is in use, 25 from left to right but passes over the bar 45 and later over the trolley pan 38.

In view of the foregoing, the operation of my apparatus will be readily understood.

Assuming the device to be erected and in 40 use in the normal manner, a trolley wheel being in the position indicated, no motor current being employed, then a current will flow through the bar 8, wire 9, magnet of the relay 2, wire 10 and trolley wire 42. A 45 second current will flow through from the bar 8 to the bar 11 by means of the trolley wheel 46 and thence through the wire 12, fuse 6, wire 13, switch 14, wire 15, relay armature or bell crank lever 17, contact 20, 50 wire 27, circuit breaker 7, wire 28, and thence through one of the coils of the double solenoid 3 to the ground. Under these circumstances, when the device is in use in the customary manner, it is common to have a 55 car go straight ahead when the trolley wheel is under the trolley pan with power off the motors. This is not essential, but it is the usual practice. If the switch-point rail 4 is in the right position it remains in 60 the right position. If it is not in the right position it is thrown into the right position. The trolley wheel 46 then runs farther along the trolley pan and leaves the rail 11 and passes on to the rail 45 65 which is directly connected to the rail 8.

The current then flows from the rail 8 to the rail 45 through the wheel 46, and thence through the wire 44 to the coil 37 which thereupon becomes energized and makes the iron of the core 34 pass into the magnetic zone of the coil 37 thereby opening the electric switch 14. The switch then remains open until the trolley wheel 46 enters upon the trolley pan 38 and then this wheel connects the bars 41 and 39 so that a current may flow through the wire 40 into the coil 36 and thence to the ground, and thereby restore the core 34 to its normal position, and close the switch 14. If power is taken through the trolley wheel 46, when in the 70 position shown, and passed to the motors, then the action is almost as above described, except that the motor current energizes the magnet of the relay 2 enough to cause the armature to be actuated (by armature is 75 meant the core 19 and bell crank lever 17 together with their incidental parts) so that the bell crank lever 17 rests against the stop 29 and then a current flows through the other coil of the solenoid 3 so that the 80 switch point is thrown in the opposite direction from that above described, if it is not 85 already in that position.

The operation of the switch 14 is precisely as above described so that the description 95 will not need repeating. It is sufficient to say that in the event last above mentioned, the other trolley pan 38 will be the one the trolley wheel 46 passes upon to actuate the switch 14. If, for any reason, the trolley 100 wheel 46 should stand on the trolley pan 1 so as to connect the bars 8 and 11, a blow-out of the fuse 6 is prevented.

The embodiment shown and described above is not the only embodiment of my invention which comes within its scope. It may be embodied in any of many forms all of which come within the scope of the annexed claims.

What I claim is,

1. In a switch operating mechanism, an electrically operated switch throwing device with circuits therein and means for opening and closing one of said circuits when the device is in use so that a trolley wheel will first open said circuit and later close the same, whereby the device is rendered inoperative during the time between the opening and closing of said circuits.

2. In a switch operating mechanism, a double solenoid and means controlled thereby for operating a switch point, a relay, two trolley pans, an electric switch and a double solenoid connected therewith, wires, and means connecting said elements so that when a trolley wheel is on a part of the first trolley pan the electric switch is open, and when this trolley wheel is on the second trolley pan the electric switch is closed.

3. In a switch operating mechanism, the

combination of an electrically operative switch throwing device, a trolley, circuit closing means operated automatically during the movement of a car for transmitting 5 current from the trolley to the switch throwing device to operate the latter in the proper direction, and an electric switch device operative with the circuit closing means and operated automatically from the trolley to 10 first open and subsequently close a part of the circuit closing means.

4. In a switch operating mechanism, the combination of an electrically operated switch throwing device, a trolley wire, two

line contactors, a relay controllable through 15 one of said line contactors for transmitting the current from the trolley wire to the switch throwing device, an electric switch opening and closing device made to open and close a portion of the circuit through 20 the relay, and connections between said electric switch opening and closing device and both of said line contactors.

ELMER S. OLMSTED.
